UNITED STATES PATENT OFFICE.

GEORGE M. HOLLEY, OF DETROIT, MICHIGAN, ASSIGNOR TO HOLLEY BROTHERS COMPANY, OF DETROIT, MICHIGAN, A CORPORATION OF MICHIGAN.

MANIFOLD CONSTRUCTION FOR EXPLOSION-ENGINES.

1,300,395.

Specification of Letters Patent. Patented Apr. 15, 1919.

Application filed September 4, 1917. Serial No. 189,667.

To all whom it may concern:

Be it known that I, GEORGE M. HOLLEY, a citizen of the United States of America, residing at Detroit, in the county of Wayne 5 and State of Michigan, have invented certain new and useful Improvements in Manifold Construction for Explosion-Engines, of which the following is a specification, reference being had therein to the accompanying drawings.

The invention relates to explosion engines of the type employing relatively non-volatile fuels, such for instance as kerosene, which require heating in forming the explosive mixture. The invention comprises the 15 novel construction of manifold and associated mechanism by which the heating effect may be adjusted according to requirements.

20 In the drawings:

Figure 1 is a longitudinal section taken on line 1—1 of Fig. 3 through a portion of the manifold showing my improvements applied thereto, the adjustment of parts being 25 such as to subject the explosive mixture to the maximum preheating effect.

Fig. 2 is a sectional plan view taken on line 2—2 of Fig. 1, and

Fig. 3 is a cross-section taken on line 3—3 30 of Fig. 2 showing the position of parts resulting in a minimum preheating of the explosive mixture.

A is the intake manifold of an explosion engine and B is the exhaust manifold thereof. C is a carbureter including a nozzle D for the liquid fuel and a mixing chamber E into which a limited quantity of air is drawn around the nozzle to operate as a vehicle for conveying the fuel. To form the explosive 35 mixture the mixed air and fuel must first be heated and then introduced into a larger volume of air to obtain the proper proportion. The necessary heat may be obtained from the exhaust gases, but it is essential to regulate this heat so as to avoid on the one 40 hand overheating and carbonization, and on the other hand under-heating and imperfect vaporization.

With my improved construction I have 45 provided a simple and convenient means of regulating the heat, the construction being as follows: F is the discharge end of the exhaust manifold arranged centrally thereof, and G is a wall or partition extending 50 longitudinally of the manifold and centrally apertured at H in alinement with the dis-

charge aperture F. I is a cylindrical valve mounted on a stem J, which slidably engages bearings K to move axially and centrally of the apertures H and F. The upper 60 end of this valve has a flaring flange L adapted to close the aperture H when arranged therein, the diameter of the valve being less than that of said aperture H so as to leave an annular space therearound in 65 a different position of adjustment. M is a heating coil surrounding the valve I and arranged in a chamber N of the manifold. The coil M is attached at one end M¹ to the mixing chamber E, while its opposite end 70 M² extends to the inlet manifold.

With the construction as thus far described, when the valve is in the position shown in Fig. 1 the flaring flange L is adjacent to the upper wall of the manifold and an annular space is formed between the cylindrical body of the valve and the edge of the aperture H. The exhaust gases will therefore pass through this annular space and come in direct contact with the coil M 80 before they are finally discharged through the aperture F. By adjusting the valve into the position shown in Fig. 3, the flaring flange L fills the aperture H preventing passage of exhaust gas therethrough. At 85 the same time this flange being removed from the upper wall of the manifold will uncover the central opening through the valve so that the exhaust gases can pass through this opening to the aperture F without coming in contact with the coil M. If the valve is adjusted to a position intermediate the two positions, just described, some of the exhaust gases will pass in contact with the coil and another portion will pass 90 through the center of the valve and out of contact with the coil. Thus by properly adjusting the valve, any desired heating effect may be produced.

Any suitable means for adjusting the 100 valve either automatic or manually-operated may be provided, but as shown the stem J is operated by a bell-crank lever O actuated by a handle P fitting a notched segment Q for holding it in different positions 105 of adjustment.

What I claim as my invention is:

1. The combination with an exhaust manifold, of a fuel heating coil arranged therein, a tubular shield for protecting said coil from 110 the exhaust gases, and means for adjusting said shield to expose the coil to said gases.

2. The combination with an exhaust manifold having a common discharge portion, of a fuel heating coil arranged within said discharge portion, a tubular shield within said 5 coil for protecting the same from the exhaust gases, and means for adjusting said shield to a position for deflecting the gases around the same and against said coil. 65
3. The combination with an exhaust manifold having a common discharge portion, of a fuel heating coil arranged in said common discharge portion, a tubular valve within said coil, seats coöperating with said valve to deflect the exhaust gases therethrough, 70 whereby the coil is shielded, and means for adjusting said valve from its seat to permit passage of the exhaust gases in contact with said coil. 75
4. The combination with an exhaust manifold having a common discharge portion, of a fuel heating coil arranged within said common discharge portion, a tubular valve within said coils, a seat coöperating with said valve to deflect the exhaust gases through the center 80 thereof and to shield the coil therefrom, and a second seat against which said valve may be adjusted for closing the passage through said valve and deflecting the gases around the same and in contact with 85 said fuel heating coil. 90
5. The combination with an exhaust manifold having a laterally-extending common discharge portion, of a fuel heating coil arranged in said portion, a tubular valve within 95 said coil having a flaring flange at one end thereof, a seat for coöperating with said flange in one position of the valve to direct the exhaust gases through the center of the valve and to shield the coil therefrom, and a 100 second seat coöperating with said flange in another position of adjustment for closing the passage through the valve and deflecting the gases around the same and against said coil. 105
6. The combination with an exhaust manifold having a laterally-extending common discharge portion, of an apertured diaphragm for separating said discharge portion from the main portion of the manifold, 110 a fuel heating coil in said discharge portion beyond said diaphragm, a tubular valve within said coil having a flaring flange for engaging the aperture in said diaphragm to compel the passage of exhaust gases through the center of the valve, shielding the coil 115 therefrom, and a seat in which said valve may be adjusted for closing communication with the center of the valve, whereby the gases are deflected around the valve and in contact with said coil. 120
7. The combination with an exhaust manifold, having a discharge portion, of a tubu- lar member within said discharge portion, a fuel heating device surrounding said tubular member and protected from the exhaust gases 65 by said member, and means for adjusting said member to a position for deflecting the gases around the same and against said fuel heating device. 70
8. The combination with an exhaust manifold having a discharge portion, of a tubular valve within said discharge portion, a fuel heating device surrounding said tubular valve, seats coöperating with said valve to deflect the exhaust gases therethrough, whereby said heating device is shielded, and means for adjusting said valve from its seat to permit passage of the exhaust gases in contact with said heating device. 75
9. The combination with an exhaust manifold having a discharge portion, of a tubular valve within said discharge portion, a fuel heating device surrounding said tubular valve, a seat coöperating with said valve to deflect the exhaust gases through the center 80 thereof and to shield the heating device therefrom, and a second seat against which said valve may be adjusted for closing the passage through said valve and deflecting the gases around the same and in contact with 85 said fuel heating device. 90
10. The combination with an exhaust manifold having a laterally-extending discharge portion, of a tubular valve within said discharge portion having a flaring flange at one 95 end thereof, a fuel heating device surrounding said tubular valve, a seat for coöperating with said flange in one position of the valve to direct the exhaust gases through the center of the valve and to shield the heating device therefrom, and a second seat coöperating with said flange in another position of adjustment for closing the passage through the valve and deflecting the gases around the same and against said heating device. 100
11. The combination with an exhaust manifold having a laterally-extending discharge portion, of an apertured diaphragm for separating said discharge portion from the main portion of the manifold, a tubular valve 110 within said discharge portion having a flaring flange for engaging the aperture in said diaphragm to compel the passage of exhaust gases through the center of the valve, a fuel heating device surrounding said tubular 115 valve and adapted to be shielded from the exhaust gases by said valve, and a seat in which said valve may be adjusted for closing communication with the center of the valve, whereby the gases are deflected around the valve and in contact with said heating device. 120

In testimony whereof I affix my signature.

GEO. M. HOLLEY.
